CLAIM

The ornamental design for a mother's blanket, as shown and described.

DESCRIPTION

FIG. 1 is a front left perspective view of a mother's blanket showing my new design;

FIG. 2 is a front view thereof;

FIG. 3 is a rear view thereof;

FIG. 4 is a left front perspective view showing actual placement of the mother's blanket around the upper body of an individual; and,

FIG. 5 is a front elevational view thereof.

The broken line showing of a woman, child, and baby bottle, in FIG. 1, a tethered toy, in FIG. 2, and a woman, in FIG. 4, is for illustrative purposes only and forms no part of the claimed design.
